(57) **CLAIM**

The ornamental design for strap for goggles, as shown and described.

DESCRIPTION

FIG. 1 is a top, rear and right side perspective view of a strap for goggles of our design.

FIG. 2 is rear view thereof.

FIG. 3 is a left side view thereof.

FIG. 4 is a right side view thereof; and,

FIG. 5 is a second right side view showing the strap for goggles in use thereof.

Elements drawn in broken lines represent environmental features that form no part of the claimed design.

1 Claim, 5 Drawing Sheets
